United States Patent Office

Des. 192,443
Patented Mar. 20, 1962

192,443

VENDING MACHINE OR SIMILAR ARTICLE

Howard E. Grant, Farmingdale, N.Y., assignor to Automatic Concessions Corporation, Westbury, N.Y., a corporation of New York

Filed May 8, 1961, Ser. No. 65,067

Term of patent 14 years

(Cl. D52—2)

Fig. 1.

Fig. 2.

Fig. 3.

FIGURE 1 is a front elevational view of a vending machine or similar article, showing my new design;

FIGURE 2 is a side elevational view thereof; and

FIGURE 3 is a top plan view thereof.

The undisclosed side of the vending machine is substantially like the side shown, and the rear is plain.

I claim:

The ornamental design for a vending machine or similar article, as shown and described.
